CLAIM

The ornamental design for a set of custom grille light for an automobile, as shown and described.

DESCRIPTION

FIG. 1 is a perspective view of a set of custom grille light for an automobile shown in an automobile showing my new design;

FIG. 2 is a perspective view of a set of custom grille light for an automobile;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof;

FIG. 8 is a right elevation view thereof;

FIG. 9 is a perspective view of another embodiment of a set of custom grille light for an automobile;

FIG. 10 is a front elevation view thereof, of which the back elevation view is a mirror image;

FIG. 11 is a top plan view thereof;

FIG. 12 is a bottom plan view thereof; and,

FIG. 13 is a right side elevation view thereof, of which the left side elevation view is a mirror image.

The broken line showing in the drawings is included for the purpose of illustrating and forms no part of the claimed design.

1 Claim, 6 Drawing Sheets
